CORK TOOL

Arti Arrighini and Robert Bell, Detroit, Mich., assignors to Rocwall Company, Detroit, Mich., a corporation of Michigan

Filed Apr. 22, 1957, Ser. No. 654,185

2 Claims. (Cl. 29—235)

This invention relates to a tool for inserting a plug in a hole.

In the construction of composition or concrete walls, the composition material is poured between laterally spaced panels of a form and allowed to harden. The panels are held together against spreading by tie rods which extend through the composition material. After the wall has hardened, the panels and the tie rods are removed. The tie rods leave holes in the wall which should be filled.

One object of this invention is to provide a tool for inserting plugs into these holes, which is of relatively simple construction yet easy to operate even by inexperienced personnel.

Another object of the invention is to provide a tool for inserting a plug in a hole of a composition wall which is smaller in cross section than the maximum cross section of the plug, the tool having provision for reducing the plug prior to its entry into the hole.

Other objects and features of the invention will become apparent as the description proceeds, especially when taken in conjunction with the accompanying drawing illustrating a preferred embodiment of the invention, wherein:

Fig. 1 is a top plan view of a tool embodying the invention.

Fig. 2 is a sectional view taken along the line 2—2 on Fig. 1 and showing the plunger in retracted position.

Fig. 3 is similar to Fig. 2 and shows the tool in operative relation to a concrete wall having a hole to be plugged, the plunger being shown in an intermediate position.

Fig. 4 is similar to Fig. 3 showing the plunger fully advanced and the plug inserted in the hole.

Fig. 5 illustrates the concrete wall after the hole has been plugged and the plugged hole sealed.

Referring now more particularly to the drawing, the tool is indicated generally by the reference numeral 10 and comprises a tubular plug holder 12. The plug holder 12 comprises the axially aligned inner and outer sections 14 and 16. The tubular sections 14 and 16 have their adjacent ends welded together as indicated at 18.

The inner section 14 has an internal surface 20 which is frusto-conical and which tapers toward the inner end 22 of the tool. The frusto-conical surface 20 constitutes a reducing die for the plug 24 which is provided to fill a hole. The plug 24 is frusto-conical and its external lateral surface tapers at approximately the same angle as the reducing die formed by the internal surface 20 of section 14. The plug is formed of a suitable material which is yieldable and resilient, such as cork.

The outer section 12 has a cylindrical bore 26 which extends from the inner end of the section outwardly to the shoulder 28. The shoulder 28 separates the bore 26 from the cylindrical bore 30 which is concentric with bore 26 but of smaller diameter. The bores 26 and 30 have a common axis which is coincident with the axis

2

of the tapered frusto-conical surface 20, and the maximum diameter of the surface 20 at its outer end is equal to the diameter of bore 26.

The inner end portion of the section 16 is formed with a slot 32 in its side wall. This slot 32 is of a length slightly greater than the length of the plug 24 and is of sufficient circumferential extent to permit the plug to be inserted into the section 16.

The plunger 34 has a cylindrical portion 36 of approximately the same diameter as bore 30 which is slidable within bore 30. At the inner end of portion 36 is an enlarged integral collar 38 which is cylindrical and of approximately the same diameter as bore 26 and slidable within bore 26. A reduced cylindrical portion 40 extends inwardly from the collar. The cylindrical portions 36, 38 and 40 are concentric and preferably of integral construction. The plunger is reciprocable within the tubular member 12 from a retracted position shown in Fig. 2 determined by the engagement of collar 38 with shoulder 28 to an advanced position indicated in Fig. 4 determined by the engagement of collar 38 with the tapering internal surface 20 which constitutes the reducing die.

In operation, the tool is placed against the composition wall W with the inner end 22 thereof bearing against the wall and with the small end of the reducing die 20 approximately concentric with the hole H. The hole H may have been made by a tie rod in the formation of the wall. It will be noted that the diameter of the reducing die at its inner end is less than the diameter of the hole H.

With the plunger 34 retracted, plug 24 is inserted through opening 32, and the plug is then driven through the reducing die and forced into the hole H by striking the outer end of the plunger 34 with a hammer. The reducing die compresses or reduces the cork plug to a diameter less than that of the hole so that the plug may be inserted with a minimum of effort. The plug is held under compression in the hole.

After the plug has been inserted, the entrance to the hole may be filled with mastic or any cement-like or sealing material indicated at 45, and the outside of the wall may be tarred as indicated at 46.

What we claim as our invention is:

1. A tool for inserting a plug in a hole of smaller cross-section than the plug, said tool comprising axially aligned inner and outer tubular sections, said inner section having a frusto-conical inner surface which tapers from the outer end of said inner section radially inwardly to the inner end thereof where it has a smaller cross-section than the hole, said outer section having a cylindrical inner surface extending from the outer end of said outer section to the inner end thereof where it merges into the outer end of said frusto-conical inner surface of said inner section, said inner surfaces of said sections being axially aligned with one another, said outer section having a lateral opening to the interior thereof for the insertion of a plug, the inner end of said inner section being flat and in a plane normal to the axis of said inner section to enable said tool to be positioned with said inner section overlying the hole and with the inner end of said inner section flush with the surface surrounding the hole, and a plunger slidably supported in said outer section for movement from a retracted position in which its inner end is at the outer side of said opening to an advanced position in which its inner end extends into and through said inner section to force a plug in said outer section through said inner section and into the hole, said frusto-conical inner surface of said inner section serving as a reducing die to facilitate the entry of the plug into the hole by compressing the plug in response to its movement through the inner section in an axially inward di-

rection, the outer end of said plunger extending outwardly beyond the outer end of said outer section in all positions thereof between said retracted and advanced positions for striking with a hammer, said cylindrical inner surface of said outer section having an outer portion closely receiving said plunger and an inner portion of greater diameter than said outer portion separated from the later by an annular shoulder, and a collar on said plunger engageable with said shoulder to determine said retracted position and with the outer end of said frusto-conical inner surface of said inner section to determine said advanced position, said collar engaging the inner portion of said cylindrical inner surface of said outer section in positions between said retracted and advanced positions for guiding said plunger in its travel between said positions while maintaining a minimum amount of frictional engagement between said plunger and tubular section.

2. A tool for inserting a solid frusto-conical plug of compressible material into a hole of smaller cross-section than the larger diameter of the plug, said tool comprising a tubular member and a plunger, said tubular member having a substantially uniform exterior diameter, and also having a portion at one end thereof having a reduced interior diameter, and a portion at the other end thereof whereat the interior diameter uniformly decreases toward said other end to a diameter smaller than the hole into which it is desired to insert the plug at said other end, said other end of said tubular member being substantially flat and extending perpendicularly to the longitudinal axis of the tubular member to provide means for contacting the surface around the hole into which it is desired to insert a plug, a lateral opening through the wall of said tubular member to allow insertion of a plug into the interior thereof, said plunger being a cylindrical member inserted within said tubular member for axial reciprocating movement with respect thereto, one end of said plunger being of substantially the same exterior diameter as the reduced interior diameter of said portion at said one end of said tubular member, the other end of said plunger having a diameter substantially the same as the

interior diameter at said other end of said tubular member, a central plunger section between said ends thereof of relatively slight axial extent and having a diameter equal to the interior diameter of said tubular member between the portions at the ends thereof whereby said plunger is restrained in the reciprocal movement thereof within said tubular member due to the contact of the central section thereof with the end portions of said tubular member and said plunger is guided in the movement thereof within said tubular member with a minimum amount of frictional contact between said plunger and tubular member, said one end of said plunger extending beyond said one end of said tubular member in all operable positions of said plunger within said tubular member, said other end of said plunger moving between a position wherein said lateral opening is between said plunger and said other end of the tubular member and a position wherein said one end of said plunger extends beyond said other end of said tubular member on reciprocation of said plunger within said tubular member, said tool being operable on movement of said plunger toward said other end of said tubular member to extrude a plug outward through said other end of said tubular member, said plug having been placed within said tubular member through said lateral opening after movement of said plunger toward said one end of said tubular member, whereby said plug is inserted into a hole on placing said one end of said tubular member against the surface surrounding the hole with the opening thereof in concentric with said hole.
